UNITED STATES PATENT OFFICE

153,814

DESIGN FOR A BUBBLE BLOWING DISPLAY DEVICE

Harry Margolis, Brooklyn, N. Y.

Application February 11, 1948, Serial No. 144,416

Term of patent 7 years

(Cl. D1—2)

To all whom it may concern:

Be it known that I, Harry Margolis, a citizen of the United States, resident of Brooklyn, in the county of Kings, city and State of New York, have invented a new, original, and ornamental Design for a Bubble Blowing Display Device, of which the following is a specification, reference being had to the accompanying drawing, forming part thereof.

The figure is a perspective view of a bubble blowing display device showing my new design.

The essential features of my new design are disclosed in full lines in the drawing.

I claim:

The ornamental design for a bubble blowing display device, substantially as shown and described.

HARRY MARGOLIS.
